US00D917967S

(12) **United States Design Patent** (10) Patent No.: **US D917,967 S**
(45) Date of Patent: **** May 4, 2021**

(54) **BLENDER CONTAINER**

(71) Applicant: **SHARKNINJA OPERATING LLC**,
Needham, MA (US)

(72) Inventors: **Michael Ting**, Boston, MA (US);
Alexander Stuart Hill, Surrey (GB);
Christopher William Hedges,
Hampshire (GB); **Jared J. Proulx**,
Needham, MA (US); **Dan Kestenbaum**,
Brookline, MA (US); **Deric Z. M. Liu**,
Guangdong (CN); **Leo Lee**, Guangdong
(CN); **Robin Yin**, Hunan (CN); **Larry
Deng**, GuangDong (CN)

(73) Assignee: **SHARKNINJA OPERATING LLC**,
Needham, MA (US)

(**) Term: **15 Years**

(21) Appl. No.: **29/740,283**

(22) Filed: **Jul. 2, 2020**

CLAIM

The ornamental design for a blender container, as shown and described.

DESCRIPTION

FIG. 1 is a perspective view of a blender container, showing our new design;

FIG. 2 is a front view of the embodiment shown in FIG. 1;
FIG. 3 is a rear view of the embodiment shown in FIG. 1;
FIG. 4 is a side view of the embodiment shown in FIG. 1;
FIG. 5 is another side view of the embodiment shown in FIG. 1;

(Continued)

FIG. 6 is a top view of the embodiment shown in FIG. 1; and, FIG. 7 is a bottom view of the embodiment shown in FIG. 1. The broken lines in the figures are for environmental purposes only and form no part of the claimed design.

1 Claim, 7 Drawing Sheets
